[57] CLAIM

The ornamental design for a table, as shown and described.

DESCRIPTION

FIG. 1 is a perspective view of a table showing my design;

FIG. 2 is an enlarged view in front elevation of the table of FIG. 1; and

FIG. 3 is a side elevational view thereof, the side not shown being a mirror image of the side shown.

FIG. 4 is a rear elevational view of the table shown in FIG. 2;

FIG. 5 is a top plan view; and

FIG. 6 is a bottom plan view thereof.
